C. A. MOORMAN

ANATOMICAL DISPLAY CASE

Filed Dec. 15, 1924

INVENTOR

C. A. MOORMAN

BY *Munn & Co*

ATTORNEYS

UNITED STATES PATENT OFFICE.

CHARLES AARON MOORMAN, OF CHICAGO, ILLINOIS.

ANATOMICAL DISPLAY CASE.

Application filed December 15, 1924. Serial No. 756,165.

To all whom it may concern:

Be it known that I, CHARLES AARON MOORMAN, a citizen of the United States, and a resident of Chicago, in the county of Cook and State of Illinois, have invented a new and useful Improvement in Anatomical Display Cases, of which the following is a full, clear, and exact description.

My invention relates to improvements in anatomical display cases, and it consists in the combinations, constructions, and arrangements herein described and claimed.

An object of my invention is to provide a display case which is intended for use by salesmen and the like for visibly acquainting the stockman with the pertinence of various hog remedies and foods.

A further object of my invention is to provide a display case having the shape of a hog and constructed with two principal parts hingedly mounted to one another which may be moved apart so as to display the internal anatomical portions of the hog.

A further object of my invention is to provide a display case in which compartments are provided in certain portions of the interior of the case for containing hog remedies, foods and the like, and in which these compartments are disposed adjacent to the portions of the hog affected by the feeding of such remedies and foods.

A further object of my invention is to provide a display case in which the compartments for containing the remedies, foods, and the like are provided with transparent covers so that the observer may see the physical appearance of the remedies and foods and thus become acquainted with their appearance.

A further object of my invention is to provide a display case in which the means for hingedly mounting the two portions of the case also serves to provide a handle by means of which the entire case may be carried.

Other objects and advantages will appear in the following specification, and the novel features of the invention will be particularly pointed in the appended claims.

My invention is illustrated in the accompanying drawings forming part of this application, in which—

Figure 1 is a side elevation of an embodiment of my invention, and

Figure 2 is a view of the display case shown in Figure 1 in open operative position.

In carrying out my invention I make use of a pair of cooperating molded metal parts 1 and 2 which, when placed in registration with one another, have the external appearance of a hog. These parts are hingedly mounted to one another by the provision of a handle member 3 having axially aligned portions 4 which are projected through lugs 5 and 6 provided on the parts 1 and 2, respectively, and having aligned openings therethrough to receive the portions 4 and the handle 3.

The parts 1 and 2 are locked into engagement with one another at the bottom by the provision of a threaded bolt 7 extending downwardly from the part 2 and having a thumb nut 8 thereupon and a slotted plate 9 which is arranged to partially encompass the bolt 7 when the parts 1 and 2 are in the position shown in Figure 1. Thus the thumb nut 8 may be turned to secure the parts against unintentional movement away from one another as in carrying.

Means for assuring proper registration of the parts 1 and 2 is provided in recesses 10 and registering lips 11 on the part 2 (see Figure 2).

The interior of the part 2 is designed to illustrate in bas-relief all the principal bones of the skeleton of the hog, as shown at 12, so that an observer may see instantly the fleshy portions of the hog.

Four containers 13, 14, 15, and 16 are formed in the part 2, and each are provided with a transparent cover through which the contents of the chambers is visible. The container 13 is filled with an assortment of minerals which are beneficial to the entire body of the hog.

The container 14 is disposed just to the back of the ribs and is filled with a laxative which has substantially the same appearance as the minerals in the container 13.

The container 15 is filled with a darker colored compound which is seen through the transparent cover and which is for the purpose of preventing the accumulation of intestinal worms.

The container 16 is filled with a composition which is for the purpose of producing flesh.

A relatively large container having a transparent cover 17 is provided at the central portion in the interior of the part 1. This container holds substantially a one-day 5 ration of a mineral mixture for hogs. This ration is a mixture containing the ingredients shown in the containers, 13, 14, 15, and 16, and is a general stabilizer and tonic which tends to increase the growth of the 10 animal in size and weight and also to aid in the prevention of disease.

From the foregoing description of the various parts of the device, the operation thereof may be readily understood. In employing 15 my improved anatomical display case, the salesman or person using the case will first place the case in an upright position, as shown in Figure 1, before the stockman. The case is an exact replica of 20 a healthy, properly fed hog, and comparisons may be made with the stock at hand, whereupon the presence of the case suggests to the stockman that certain elements 25 in the flesh or general health of his stock is at fault.

Having thus properly introduced the topic of hog remedies, and foods, the case is opened to the position shown in Figure 2 by unfastening the thumbnut 8. 30 When in this position, the salesman may definitely inform the stockman as to the various remedies and foods necessary for the good health of his stock. It will be noted that the containers having the ingredients 35 are placed in positions pertinent to the contents thereof. This presentation, visually, of the various organs of the hog and the associate remedies and foods permits the stockman to instantly realize what 40 may be lacking in his own stock and what remedies it is necessary to employ to properly build up unhealthy or lean stock.

When the salesman has finished his interview, the case is closed, as in Figure 1, and 45 it may be readily carried about from place to place, and, since constructed of metal, preferably aluminum there is little possibility of damage to the case, and it may be carried with ease because of its lightness.

50 I claim:

1. An anatomical display case of the character described comprising a pair of hingedly connected cooperating members having the outward appearance, when in 55 registration with one another, of one of a species of domestic stock, one of said cooperating members having its interior walls formed to designate the internal physio-

logical members of the species, and being further provided with compartments, each 60 of said compartments having a transparent cover and being filled with ingredients beneficial to that portion of the animal in the vicinity of the container.

2. An anatomical display case of the character described comprising a pair of hingedly connected cooperating members having the outward appearance, when in registration with one another, of one of a 65 species of domestic stock, one of said cooperating members having its interior walls formed to designate the skeleton of the species, and being further provided with compartments, each of said compartments having a transparent cover and being filled 70 with ingredients beneficial to that portion 75 of the animal in the vicinity of the container.

3. An anatomical display case of the character described comprising a pair of 80 hingedly connected cooperating members having the outward appearance, when in registration with one another, of one of a species of domestic stock, one of said cooperating members having its interior walls 85 formed to designate the skeleton of the species, and being further provided with compartments, each of said compartments having a transparent cover and being filled with ingredients beneficial to that portion 90 of the animal in the vicinity of the container, and a relatively large container having 95 a transparent cover formed on the remaining cooperating part of the case, said container being filled with a one-day ration of food beneficial to the animal.

4. An anatomical display case of the character described comprising a pair of cooperating parts hingedly mounted to one another by the provision of a bent rigid rod 100 fashioned to serve as a handle for carrying the case, said cooperating parts having the outward appearance, when in registration with one another, of one of a species of domestic stock, one of said members being 105 fashioned with its inner wall to represent a bas-relief of certain physiological members of the species represented by the exterior contour of the case, and containers having transparent covers formed on said cooperating parts in predetermined positions relative to the physiological members, said container being filled with ingredients pertaining and beneficial to the region of the animal where the containers are disposed.

CHARLES AARON MOORMAN.
